UNITED STATES PATENT OFFICE.

JOHN P. WEISS, OF SOUTH BEND, INDIANA.

DESIGN FOR AN ELECTRIC TABLE LAMP.

Application filed March 15, 1928. Serial No. 25,871. Term of patent 7 years.

To all whom it may concern:

Be it known that I, JOHN P. WEISS, a citizen of the United States, residing at South Bend, in the county of St. Joseph and State of Indiana, have invented a new, original, and ornamental Design for an Electric Table Lamp, of which the following is a specification, reference being had to the accompanying drawings, forming part thereof:

The figure is a perspective view of an electric table lamp, showing my new design.

I claim:

The ornamental design for an electric table lamp as shown.

JOHN P. WEISS.
